BOILER

William F. Gerhardt, Richmond, Va.

Application February 5, 1936, Serial No. 62,534

3 Claims. (Cl. 122—225)

This invention relates to boilers and the object of the invention is to provide a boiler adapted for domestic heating purposes.

A further object of the invention is to provide a boiler whereby an oil burner may be used in conjunction therewith.

A further object of the invention is to provide a boiler having improved means for the circulation of water therethrough, and also for the circulation of the products of combustion to insure a thorough heating of the water.

The invention together with its objects and advantages will be best understood from a study of the following description taken in connection with the accompanying drawings wherein:

Figure 1 is a side elevational view of the boiler embodying the features of the present invention.

Figure 2 is a view similar to Figure 1 but with a lower panel removed.

Figure 3 is a vertical sectional view through the boiler and taken substantially on the line 3—3 of Figure 4.

Figure 4 is a horizontal sectional view through the boiler.

Figure 5 is a fragmentary rear elevational view of the boiler.

Figure 6 is a fragmentary detail sectional view taken through one of the sections of the water circulating unit.

Figure 7 is an elevational view of one of the sections.

Figure 8 is a fragmentary detail view showing the manner of connecting the sections together.

Referring to the drawings by reference numerals it will be seen that the boiler comprises a casing 5 including a top 6, a rear wall or panel 7 which terminates short of the bottom of the boiler, side panels 8 which also terminate short of the bottom of the boiler and lower side panels 9.

Suitably supported at the lower edges of the panels 7 and 8 is a short bottom panel section 10 which merges into a vertical partition panel 11 disposed in spaced parallel relation to the panel 8. The panel 11 forms with the bottom panel 10

and the removable side panels 9 a burner compartment 12 opening at the rear of the boiler and adapted to accommodate a conventional oil burner 13 as shown in Figure 2. At the open front side of the chamber 12 the panel 10 is braced by suitable standards 14a as shown.

The interior of the casing thus constructed is lined as clearly shown in Figure 3 with asbestos or other insulating material 14.

Arranged in the casing above the compartment or chamber 12 is a plurality of hollow rectangular shaped sections 15, each section having spaced hollow baffles 16 connecting opposite sides thereof, the baffles 16 in the present instance being substantially diamond shaped in cross section.

The sections 15 are arranged between a front section 17 of substantially the same dimensions as the sections 15, and a section 18 which has a baffle equipped portion substantially identical in construction with the sections 15 and 17 but which also has integral therewith a hollow shell 15 portion which fits conformably in the front portion of the casing 5 and includes inner walls 19 and outer walls 20 spaced from the inner wall 19, the lower portions of which walls extend downwardly between the lower portion of the panel 8 20 and partition panel 11.

All of the sections 15, and section 18 are so arranged, and as shown, relative to one another as to have the baffles of one section staggered with respect to the baffles of the next adjacent section.

Each of the sections is preferably made of cast iron substantially in the form of parallelopipeds which are assembled to provide a chamber for heating the water within the hollows 21 of the sides of the sections 15, the hollow 26 of section 30 17, and also within the hollow 22 formed by the wall portions 19 and 20 of the section 18; as well as for heating the water within the hollow 23 of the tubular baffles 16 with which each of the sections 15 and section 18 is provided as shown.

Further each of the sections is suitably provided as shown in Figure 8 with openings 24 arranged at diagonally disposed corners thereof and providing for the entrance and exit of water from each of the sections. When the sections 40 are assembled the openings 24 align, as is thought apparent, and as shown in Figure 8 have fitted therein the ends of coupling tubes 25 for a circulation of water through the assembled sections.

The end section 17 is provided at the top thereof with an outlet 27 coupled in any suitable manner with the feed pipe 28 which leads from the boiler to the radiators (not shown).

The section 17 as shown is also provided with a suitable cleanout opening 29 therethrough, and

with a flue opening 30 adapted to be coupled in the usual manner with the stack 31.

For the opening 29 the panel 7 is provided with a suitable door 32.

5 The outer wall 20 of combustion chamber 40 formed integral with member 18 adjacent the bottom thereof is provided with a suitable inlet 33 adapted to be connected with the return side 34 of the water circulating system and if desired, 10 and as shown, an electric booster pump 35 may be inserted in the line between the return conduit 34 and the inlet 33. In the lower portion thereof the combustion chamber 40 has extending through the walls thereof an inlet opening 36 15 that accommodates the barrel 13a of the oil burner as will be clear from a study of Figures 2 and 3. Also the combustion chamber 40 is suitably provided with a clean-out opening 37 and for this opening the rear panel 8 is provided with a 20 clean-out door 38. From the above detailed description it will be appreciated that water from the return side 34 will pass into the hollow 22 of section 18 and from section 18 pass through the successive sections 15, and section 17, passing 25 from the latter through the feed line 28, the water circulating through the hollows of the sections as well as through the hollows of the tubes 16.

The products of combustion will pass upwardly within the confines of the combustion chamber 30 40 and from this chamber the products of combustion will take a staggered course between the baffles 16 to pass to the stack 31 through the flue 30, the products of combustion thus heating the water circulating through the sections 18, 15 and 35 17 as is thought apparent.

Access to the combustion chamber above referred to and indicated by the reference numeral 40 is had from one side thereof through an opening in the lower portion of the chamber 40, which 40 opening is closed by a suitable cover plate 41. Access to the plate 41 may be had by removing the adjacent side panel 9 which is releasably secured in position in any suitable manner by latches or the like, the handles of which are shown 45 in Figure 1 and indicated by the reference numeral 42.

Also in one side panel 8 there may be provided a suitable "peep" hole for which there is provided a door 43.

50 Also for using some of the water circulating within the hollows of the section for heating the water provided for domestic purposes, such as for bathing or the like there is provided a suitable heater 44 in the form of a casing in which is 55 arranged a suitable coil, the casing being connected by piping 45 with one of the sections 15 and the coil is connected by piping 46 with the house water system.

60 Adverting again to the assemblage of the sections 15, 17 and 18, there are interposed between these sections suitable gaskets 47 and for positively securing the sections together tie rods 48 are employed, and to accommodate these tie rods 65 the sections are provided at diagonal corners thereof with apertured lugs 49 as best shown in Figures 7 and 8.

Also to protect the oil burner 13 there is suitably mounted within the chamber 12 above the oil burner a shield 49 opposite portions of which are 70 inclined as clearly shown in Figure 5 and the shield will serve to direct any particle of condensation to either side of the oil burner.

If desired, and as shown, the section 18 is provided with a baffle "B" extending transversely

thereof adjacent the lower end of the tube equipped part of said section.

Having thus described the invention, what is claimed as new is:

1. In a boiler of the class described, a casing 5 having a burner compartment in the bottom thereof, a heat exchange device arranged within the casing and comprising a plurality of hollow substantially rectangular sections arranged above the burner compartment, said sections including 10 a pair of end sections and a plurality of intermediate sections, said intermediate sections and one of said end sections respectively having spaced hollow baffles connecting the top and bottom sides thereof, said intermediate sections and said one 15 section being substantially of frame like form, and the other of said end sections being in the form of a hollow plate, said intermediate section and the first named end section being so arranged relative to one another as to have the baffles of 20 one of said sections staggered with respect to the baffles of the next adjacent one of said sections, means connecting said sections in communication one with the other to provide for a flow of water successively through the sections, and the first 25 named end section having integral therewith a combustion chamber having inner and outer spaced walls providing a water chamber connected with and communicating with said first named end section, said combustion chamber extending downwardly to one side of the burner compartment and opening into said burner compartment, inlet means for the space between the walls of the combustion chamber, and outlet means connected with the second named end 30 sections whereby to provide for a circulation of water through the space between the walls of the combustion chamber and through the sections of the heat exchange device, the arrangement being such that the water circulating through the heat 35 exchange device will be heated by the products of combustion passing from the combustion chamber and circulating about the baffles of said section.

2. In a boiler of the class described, a casing 45 having a rear bottom wall section and a raised forward bottom wall section together with a vertical wall connecting the bottom wall sections; and a heat exchange device comprising a plurality of hollow frame-like sections arranged within 50 the casing and resting on the forward bottom wall section, together with a hollow walled shell-like section having the lower portion resting on the rear bottom wall section and an upper portion in a line with the aforementioned sections of the heat 55 exchange device, means connecting all of the sections of said heat device in communication one with the other to provide for a flow of water therethrough, and said casing forwardly of said vertical wall presenting a chamber for a burner, and said 60 hollow walled shell-like section of the heat exchange device and the aforementioned vertical wall being provided with substantially aligned openings to accommodate the barrel of an oil burner or analogous burner arranged within the 65 burner chamber.

3. In a boiler of the class described, a casing having a rear bottom wall section, and a raised forward bottom wall section together with a vertical wall connecting the bottom wall sections; and a heat exchange device arranged within said 70 casing and including a plurality of complementary sections arranged within the casing, each of said sections having hollow top, bottom and side members and hollow baffles connecting the top and 75

bottom members, certain of said sections being disposed above the raised forward bottom wall section of said casing, and the inner endmost one of said sections having integral therewith 5 a hollow shell-like combustion chamber, the lower portion of which extends downwardly behind said vertical wall and is provided in alignment

with an opening in said vertical wall with an opening to receive the barrel of an oil burner or the like arranged within the casing forwardly of said vertical wall; and means connecting the sections of the heat exchange device to provide for a circulation of water through the sections. 5

WILLIAM F. GERHARDT.
